MACHINE FOR SHAPING UPPERS OVER
LASTS

Bernhardt Jorgensen, Marblehead, Mass., assignor to United Shoe Machinery Corporation, Borough of Flemington, N. J., a corporation of New Jersey

Application May 7, 1940, Serial No. 333,792

30 Claims. (Cl. 12—12)

This invention relates to machines for shaping uppers over lasts, and is herein illustrated as applied to a lasting machine of the type disclosed in United States Letters Patent No. 1,843,232, granted on February 2, 1932, on an application of mine. Such a machine includes in its organization means for laying the margin of an upper inwardly over an insole on a last along the opposite sides of the last, and an object of the present invention is to provide improved means for holding the side marginal portions of the insole close to the bottom of the last, especially along the shank portion of the insole, so that the upper will be properly lasted over them. In various novel aspects, however, the invention is not limited to means for controlling the shank portion of an insole, nor is it limited to machines of the particular type to which it is herein illustrated as applied.

A machine constructed as disclosed in the above-mentioned Letters Patent is provided with opposite side-lasting mechanisms which receive positioning movements toward each last and shoe widthwise thereof prior to the starting of the power operation of the machine, so that they assume operating positions determined by the shoe, the mechanisms including fingers which act thereafter through flexible straps to lay the margin of the upper inwardly over the insole. After thus operating on the upper at the shank portion of the shoe, the side-lasting mechanisms are moved lengthwise of the shoe toward its toe end and then operate a second time at the ball portion of the shoe. It is desirable especially at the shank portion of the shoe to press the side marginal portions of the insole against the bottom of the last preparatory to the lasting of the upper inwardly over them, and accordingly there has been provided heretofore a shank-holddown device which is supported independently of the side-lasting mechanisms and is swung downwardly into engagement with the insole about an axis extending widthwise of the shoe shortly after the starting of the power operation of the machine, as disclosed in the above-mentioned Letters Patent.

An object of the present invention is to provide improved holddown means adapted to operate on shoes of different sizes and shapes in such manner as to produce the most satisfactory results in the lasting of each shoe. For the purposes in view, the construction herein shown comprises holddowns which are supported respectively by the opposite side-lasting mechanisms themselves and are so controlled as to act in the most effec-

tive manner on the portions of the margin of the insole over which the margin of the upper is laid by these mechanisms. In order that there may be ample room for the presentation of the shoe in position to be operated upon, provision is afforded for spacing the holddowns initially well apart widthwise of the shoe and for imparting to them additional positioning movements widthwise of the shoe relatively to the side-lasting mechanisms when these mechanisms receive their positioning movements toward the sides of the shoe. In this manner the holddowns are carried to positions accurately determined with reference to the side marginal portions of the insole, provision being afforded for adjustments to vary the positions which they thus assume. Thereafter, shortly after the beginning of the power operation of the machine, the holddowns are moved heightwise of the shoe into engagement with the insole, the construction herein shown comprising for this purpose devices which are carried by the side-lasting mechanisms and are operated by compressed air. In proper time relation to the laying of the margin of the upper inwardly over the insole these devices are so controlled as to release the holddowns, whereupon the latter are withdrawn from the paths of movement of the overlaying members. The movement of the holddowns into engagement with the insole thus occurs only in the operation of the side-lasting mechanisms at the shank portion of the shoe, the devices which are operated by compressed air remaining idle during the second operation of these mechanisms at the ball portion of the shoe where there is no special need for controlling the margin of the insole. While compressed air is thus used in the machine herein shown for operating the holddowns, the invention is not limited to the use of operating fluid of that particular character.

In accordance with a further feature, the invention provides a holddown of novel construction such as to insure that the portion of the margin of an insole controlled thereby will be held throughout its length in proper relation to the last. For the purpose in view, flexible resilient means, herein illustrated as comprising a coil spring extending lengthwise along the margin of the insole, is utilized to press the margin of the insole against the bottom of the last. For controlling particularly the margin of the shank portion of the insole, the construction shown comprises two such springs in alignment with each other, and a resilient wire extending into the openings in the springs to assist in supporting

them, both the wire and the springs being flexibly yieldable heightwise of the last to conform to the contour of the last and insole and the holdown being pressed upon the insole by force applied thereto between the two springs.

The above and other features of the invention, including various novel details of construction and combinations of parts, will now be more particularly described with reference to the accompanying drawings and thereafter pointed out in the claims.

In the drawings,

Fig. 1 is a view partly in vertical section from front to rear and partly in elevation of portions of a machine of the illustrated type with the present invention embodied therein, the parts being shown in the positions which they occupy shortly after the starting of the power operation of the machine;

Fig. 2 is a view for the most part similar to a portion of Fig. 1, but showing the parts as they appear immediately prior to the starting of the machine;

Fig. 3 is a view similar to a portion of Fig. 2, but showing the parts as they appear before the side-lasting mechanisms have received their positioning movements toward the sides of the shoe;

Fig. 4 is a view partly in plan and partly in section on the line IV—IV of Fig. 2; and

Fig. 5 is a section substantially on the line V—V of Fig. 2.

As fully disclosed in the previously mentioned Letters Patent, a machine of the illustrated type is provided with shoe-supporting means, not herein shown, which is moved a short distance downwardly with the shoe early in the power operation of the machine by members, also not herein shown, which engage the bottom of the shoe. For lasting the sides of the shoe between its toe and heel-end portions such a machine is provided with opposite side-lasting mechanisms which in the construction herein shown are for the most part substantially like the mechanisms disclosed in the above-mentioned Letters Patent, although differing therefrom in certain respects as will be hereinafter explained. Each of these side-lasting mechanisms comprises a casing 2 mounted to swing toward and from the side of the shoe on a rod 4 which is movable to carry the casing and other parts of the mechanism lengthwise of the shoe toward its toe end preparatory to a second operation of the mechanism on the shoe after it has operated on the upper at the shank portion of the shoe. Mounted to swing about each rod 4 within the casing 2 is an arm 6 arranged to control a plurality of lasting fingers 8 and a plurality of flexible lasting straps 10 extending over the ends of the fingers. In the construction herein shown the fingers 8 of each side-lasting mechanism are mounted between their inner and outer ends for swinging movements heightwise of the shoe about a rod 12 supported in two upwardly extending side portions 14 of a bracket 16 fast on the upper end of the arm 6, and the straps 10 are connected at one end by a rod 18 extending through loops on the straps to a spring 20 which is connected to a pin 22 on one of the fingers, so that the spring tends to hold the straps taut over the ends of the fingers. At their other ends the straps 10 are fastened to blocks 24 pivotally mounted at 26 on arms 28 which are pivoted at 30 on the casing 2 for swinging movements laterally of the shoe, some

of the arms being controlled by spring-pressed plungers 32 and others by springs 34 against the resistance of which the arms may yield laterally of the shoe in response to pressure of the shoe on the straps and the blocks 24. Underlying the fingers 8 are spring-pressed plungers 36 which tend to swing the inner end portions of the fingers upwardly and thus assist in holding the straps 10 in a taut condition, the plungers being mounted in the bracket 16. Initially the casings 2 and the arms 6 of the side-lasting mechanisms are held in retracted positions with the straps 10 and the blocks 24 spaced from the shoe, as illustrated in Fig. 3 with reference to one of the mechanisms, and prior to the starting of the power operation of the machine, under control of means hereinafter described, the arms and the casings are swung inwardly to carry the straps into engagement with the sides of the shoe as illustrated in Fig. 2. Early in the power operation of the machine the shoe is forced downwardly to cause the straps to wipe the upper heightwise of the last, and thereafter, by further swinging movements of the arms 6, the fingers 8 are forced inwardly over the shoe bottom to cause them to act through the straps 10 to lay the margin of the upper inwardly over the insole into position to adhere to the insole.

The casings 2 are connected together by a spring 38 which tends to swing them inwardly toward the shoe and against the resistance of which they are held initially in their outermost positions by the arms 6, each arm being provided for this purpose with a stud 40 which extends through a slot 42 in the casing 2 and initially engages the casing at the outer end of the slot. For controlling and operating the arms 6 there are provided toggle links 44 which are connected to pins 46 on the arms and are pivotally and slidably mounted at their inner ends on a rod 48. This rod is supported on the upper end of a depending link 50 which is pivotally connected at its lower end to a lever 52 mounted to swing about a rod 54 on the frame. The lever 52 is connected by a link 56 to another lever 58 mounted to swing about a shaft 60 with which the machine is provided. The lever 58 carries a roll 62 arranged to be engaged by a path cam 64 formed in a cam wheel 66 fast on a power-operated cam shaft 68. Initially the side-lasting mechanisms are held retracted from the shoe as illustrated in Fig. 3 by a latch lever 70 which by engaging the end of the lever 52 underneath holds this lever uplifted with the toggle 44 in a substantially straightened condition. A plunger 72 against which the operator pushes prior to the starting of the power operation of the machine is arranged to act through a rod 74 on the lever 70 to swing this lever out from under the lever 52, thus releasing the side-lasting mechanisms and permitting them to be swung inwardly by the spring 38 to apply the straps 10 to the sides of the shoe in the manner illustrated in Fig. 2. The path cam 64 is enlarged at 76 to permit such positioning movements of the mechanisms. Shortly after the beginning of the power operation of the machine the shoe is forced downwardly to cause the straps 10 to wipe the upper heightwise of the last, the shoe thus assuming the position illustrated in Fig. 1. Thereafter the cam 64 acts on the lever 58 to swing the arms 6 farther inwardly and thus cause the fingers 8 to act through the straps 10 to lay the margin of the upper over the insole. The cam is so formed as to

impart such inward movements to the arms twice in each cycle of operations of the machine and to swing the arms and the casings 2 outwardly away from the shoe between the two inward movements of the arms to permit the side-lasting mechanisms to be advanced lengthwise of the shoe by the rods 4 from their first operating positions at the shank portion of the shoe to their second operating positions at the ball portion of the shoe.

When the lasting fingers 8 are forced inwardly over the bottom of the shoe as above described, the straps 10 controlled by the springs 20 tend to swing the inner end portions of the fingers downwardly toward the shoe bottom by their pressure on the fingers. The machine is further provided with means arranged to act on the outer end portions of the fingers to assist in swinging their inner ends downwardly and thus insure that adequate downward pressure will be applied to the margin of the upper. For this purpose each of the toggle links 44 is provided with an arm 78 extending outwardly beyond the pin 46 and pivotally connected to a sleeve member 80 slidably mounted on an upwardly extending rod 82. Each rod 82 has fast on its upper end a holder 84 guided between a pair of lugs 86 on the arm 6, only one of each pair of lugs being visible in the drawings. Pins 88, only one of which is shown, extend inwardly from the lugs 86 over portions of the holder 84 and thus confine the holder to the space between the lugs while permitting it to move upward or downward relatively to the arm 6. Supported on each holder 84, in the manner fully illustrated in the previously mentioned Letters Patent, are members 90 arranged respectively to underlie the outer ends of the several fingers 8 associated therewith and thus to swing these ends of the fingers upwardly to impart corresponding downward movements to their inner ends in response to upward movement of the holder. Such upward movement is imparted to the holder 84 through a spring 92 mounted on the rod 82 between the holder and the sleeve member 80. Initially the members 90 are spaced below the fingers 8, as illustrated in Fig. 3, and, accordingly, when the side-lasting mechanisms are moved inwardly toward the shoe by the spring 38 upon their release by the movement of the plunger 72, the members 90 are moved upwardly toward the fingers without acting on the fingers. When further swinging movements are thereafter imparted to the toggle links 44 in the power operation of the machine to cause the arms 6 to force the fingers 8 inwardly over the insole, the upward swinging movements imparted to the arms 78 by the swinging of the toggle links serve to raise the holders 84 still farther and thus to cause the members 90 to swing the fingers 8 in the directions to apply downward pressure to the margin of the upper over the insole.

As thus far described the construction herein shown, except as noted, is substantially as disclosed in the previously mentioned Letters Patent. For purposes of this invention the machine is provided with two holddowns 94 arranged to engage the opposite side marginal portions of the insole along the shank portion of the shoe bottom to insure that the insole will be close to the bottom of the last as the margin of the upper is laid inwardly over it by the fingers 8 and the straps 10. Each holddown 94 comprises a pair of coil springs 96 in alignment with each other 75

and surrounding a resilient wire 98 of smaller diameter than the openings in the springs. The wire is supported midway between its opposite ends, in a location between the springs, by a holder 100 which is fast on a plate 102. The inner ends of the two springs are mounted on studs 104 projecting from the holder 100 and of greater diameter than the wire 98, and their outer ends are mounted on studs 106, also of greater diameter than the wire, which are fast on the wire and are provided with heads to hold the springs in place. It will be evident, therefore, that when the holddown is applied to the insole the springs 96 and the wire 98 are together flexibly yieldable heightwise of the shoe to conform to the contour of the last and insole, portions of the wire and of the springs being also relatively yieldable.

Each plate 102 is curved so that the end portion thereof to which the holddown is attached extends downwardly toward the shoe and its other end portion extends outward laterally of the shoe. The outer end portion of the plate is fastened to a block 104, and extending outwardly from this block in fixed relation thereto are two bars 106 spaced a short distance apart. Fast in the block 104 is a rod 108 the opposite ends of which extend into slots 110 formed in the side portions 14 of the bracket 16. It will thus be seen that the block 104 and the plate 102 serve as one arm of a lever 111 of which the two bars 106 serve as the other arm, the lever being mounted for swinging movement heightwise of the shoe about the axis of the rod 108. Extending into slots 112 provided in the bars 106 are studs 114 which are formed on a plate 116 fastened by means of a screw 118 in a slot in the upper end of a piston 120 which is movable upwardly and downwardly in a cylinder 122 fast on the casing 2. When the piston is moved upwardly, therefore, the holddown 94 is swung downwardly toward the shoe, and when the piston is lowered the holddown is lifted from the shoe.

Pivots mounted on each rod 108 are two links 124 which extend outwardly from the rod and are pivotally connected at their outer ends to downwardly extending arms 126 (Fig. 5) of bell-crank levers 128 mounted to swing about a rod 130 which is supported in the sides 14 of the bracket 16. The bell-crank levers 128 have other arms 132 which are pivotally connected to a yoke member 134, and through an opening in this yoke member extends a rod 136 which is threaded at its lower end in the previously mentioned holder 84. Between this yoke member and a collar 138 fast on the rod 136 is a spring 140, and between the yoke member and a hand wheel 142 fast on the upper end of the rod 136 is a spring 144. It will thus be seen that through the springs 140 and 144 swinging movements are imparted to the bell-crank levers 128 in response to upward and downward movements of the rod 136 resulting from the upward and downward movements of the holder 84 to which the rod is fastened. Accordingly, when the holder 84 of each of the opposite side-lasting mechanisms is moved upwardly toward the fingers 8 as these mechanisms are moved inwardly toward the shoe by the spring 38 prior to the starting of the power operation of the machine, the corresponding upward movement of each rod 136 serves through the bell-crank levers 128 and the links 124 to move the rod 108 inwardly along the slots 110 and thus by bodily movement of the lever 111 to move the holddown 94 from an initial retracted

position in which it is substantially in engagement with the straps 10 as illustrated in Fig. 3, to a position substantially over the marginal portion of the insole, as illustrated in Fig. 2. As the holdown is thus moved inwardly, the bars 106 slide along the studs 114 of the plate 116 which is fast on the piston 120. The position to which each holdown is thus carried may be varied by turning the corresponding rod 136 by means of the hand wheel 142 thereon.

Each piston 120 is held normally in its lowest position in the cylinder 122 by a spring 146 connected at its lower end to the cylinder and at its upper end to an arm 148 fastened to the piston by the screw 118. Accordingly, the holdowns 94 are held upright when they are in their initial positions and as they are moved inwardly to positions over the insole as illustrated in Fig. 2. Shortly after the starting of the power operation of the machine the two pistons 120 are forced upwardly by compressed air admitted to the cylinders 122 to move the holdowns into engagement with the insole as illustrated in Fig. 1. For this purpose the two cylinders communicate through pipes 150 with a pipe 151 leading to a chamber 152 (Fig. 2) formed partly in a plate 154 and partly in a tube 156 fastened tightly between the plate and a bracket 158 by bolts 160 which secure the plate to the bracket. The bracket 158 is supported in a fixed position on a rod 162 (Fig. 1) with which the machine is provided. The chamber 152 in the tube 156 is separated from another chamber 164 formed partly in the tube and partly in the bracket 158 by a web 166 in the tube. The chamber 164 communicates through a pipe 168 with any suitable source of compressed air which may be an accumulator fed by a pump on the machine or may be a source of factory supply. Mounted on the tube 156 is a sleeve valve 170 provided with an annular chamber 172 arranged to communicate with ports 174 extending through the tube 156 into the chamber 164 and with ports 176 extending through the tube into the chamber 152. When the sleeve valve 170 is in its lowest position against the bracket 158, as illustrated in Fig. 2, communication between the ports 174 and the ports 176 through the annular chamber 172 is interrupted, and one of the ports 176 registers with an exhaust port 178 in the valve, so that the pistons 120 are maintained by the springs 146 in their lowest positions. The valve 170 is controlled by a lever 180 the outer end of which is forked and carries pins 182 extending into an annular groove 184 in the valve. Suitable means, not shown, is provided for preventing the valve from turning on the tube. The lever 180 is pivoted at 186 on the bracket 158 and is controlled by a spring 188 which tends to hold the valve in its lowest position. Mounted on the inner end of the lever is a roll 190 arranged to be engaged by a cam 192 on the cam shaft 68. This cam is so arranged that shortly after the starting of the power operation of the machine, substantially at the time when the shoe is moved downward relatively to the straps 10 as hereinbefore described, the valve 170 is moved upwardly by the lever 180 to establish communication between the ports 174 and 176 and thus to admit compressed air into the cylinders 122 to move the pistons 120 upwardly and thereby to move the holdowns 94 into their operative positions. The valve 170 is held in this position until the fingers 8 have started to lay the margin of the upper in-

wardly over the insole, whereupon the cam 192 passes beyond the roll 190 and the valve is returned to its lowest position by the spring 188 to stop the delivery of compressed air to the cylinders 122 and to permit the exhaust of the air in the cylinders through the port 178. This permits the holdowns to be moved upwardly away from the insole by the springs 146.

The manner of operation of the machine, in so far as it is of interest with reference to the present invention, will now be briefly summarized. As more fully disclosed in the previously mentioned Letters Patent, the operator moves the plunger 72 to release the opposite side-lasting mechanisms before starting the power operation of the machine. A machine of this type is commonly used for lasting tennis shoes or the like the uppers and insoles of which are loosely assembled on the lasts, and when the operator thus releases the side-lasting mechanisms he is accustomed to control the upper with his fingers until it is clamped against the sides of the last by these mechanisms the inward movements of which are effected by the action of the spring 38 on the casings 2. As illustrated in Fig. 2, the upper is thus clamped by the several arms 28 acting through the blocks 24 and the straps 10, the plungers 32 and the springs 34 which control these arms yielding more or less until their resistance balances the force of the spring 38. By reason of the swinging of the toggle links 44 as the side-lasting mechanisms are thus moved inwardly toward the shoe, the holders 84 are moved upwardly toward the outer end portions of the lasting fingers 8 and by their upward movements cause the rods 136 mounted thereon to swing the bell-crank levers 128 and thereby to move the holdowns 94 relatively to the side-lasting mechanisms from the positions illustrated in Fig. 3 to the positions illustrated in Fig. 2 where they are over the bottom face of the last ready to engage the side marginal portions of the insole when they are thereafter swung downwardly. While holding the insole in place with his fingers the operator then starts the power operation of the machine. Immediately after the starting of the machine the last and shoe are moved downwardly from the position illustrated in Fig. 2 to that illustrated in Fig. 1, causing the straps 10 to wipe the sides of the upper heightwise of the last toward the edges of the shank portion of the insole. At substantially the same time the valve 170 is operated by the cam 192 to admit compressed air to the cylinders 122, so that the pistons 120 are forced upwardly and move the holdowns 94 into positions to press the side marginal portions of the insole against the last, as illustrated in Fig. 1. Thereafter the cam 64 swings the inner ends of the toggle links 44 farther downwardly to swing the arms 6 inwardly toward the shoe relatively to the casings 2 and thereby to cause the fingers 8, acting through the straps 10, to lay the marginal portions of the upper inwardly over the insole. As the fingers are thus moved inwardly their inner end portions are swung downwardly by further upward movements of the holders 84 to cause them to press the upper down on the insole. In such further upward movements of the holders 84 the rods 136 act on the springs 140 with a tendency to move the holdowns inwardly over the insole, but the holdowns remain close enough to the straps 10 to press the marginal portions of the upper against the straps and thus

insure that the upper will be lasted tightly over the edges of the insole. Just after the fingers 8 begin to lay the margin of the upper inwardly over the insole the cam 192 releases the valve 170, whereupon the valve is returned to its initial position and the air in the cylinders 122 is exhausted through the port 178 of the valve. The holdowns 94 are, accordingly, lifted by the springs 146 away from the insole out of the paths of movement of the fingers 8 and the straps 10. Thereafter, in the continued operation of the machine, the side-lasting mechanisms are moved outwardly away from the shoe, are moved lengthwise of the shoe toward its toe end, and are again operated to last the ball portion of the shoe, as disclosed in the previously mentioned Letters Patent. During these operations the holdowns 94 are maintained idly in their raised positions, although moving outward and inward widthwise of the shoe, since the valve 170 remains in its exhaust position. It will be understood that at the end of the cycle of operations of the machine the holdowns are again positioned as illustrated in Fig. 3.

Having described the invention, what I claim as new and desire to secure by Letters Patent of the United States is:

1. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said mechanism for engaging the marginal portion of the insole and pressing it against the bottom of the last before the margin of the upper is laid inwardly over it, and automatic means for imparting to said holdown in addition to positioning movement received from said lasting mechanism a further movement relatively to said mechanism in substantially the same direction as the positioning movement of said mechanism to position it in proper relation to the margin of the insole.

2. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said mechanism for engaging the marginal portion of the insole and pressing it against the bottom of the last before the margin of the upper is laid inwardly over it, and means also carried by said lasting mechanism for moving the holdown relatively to said mechanism to a position opposite the bottom face of the last in the course of the positioning movement of said mechanism.

3. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said mechanism for engaging the marginal portion of the insole and pressing it against the bottom of the last before the margin of the upper is laid inwardly over it, automatic means for imparting to said holdown in addition to positioning move-

ment received from said lasting mechanism a further movement relatively to said mechanism to a position opposite the bottom face of the last, and additional means for moving the holdown heightwise of the last into engagement with the insole.

4. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said mechanism for engaging the marginal portion of the insole and pressing it against the bottom of the last before the margin of the upper is laid inwardly over it, means also carried by said lasting mechanism for automatically moving the holdown relatively to said mechanism to a position opposite the bottom face of the last in the course of the positioning movement of said mechanism, and additional means carried by said lasting mechanism for thereafter moving the holdown heightwise of the last into engagement with the insole.

5. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown for engaging the marginal portion of the insole and pressing it against the bottom of the last before the margin of the upper is laid inwardly over it, a lever supported on said lasting mechanism and on which said holdown is mounted, means for imparting to said lever bodily movement relatively to said lasting mechanism to carry the holdown to a position opposite the bottom face of the last in the course of the positioning movement of said mechanism, and means carried by said lasting mechanism for thereafter swinging said lever heightwise of the last to move the holdown into engagement with the insole.

6. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said mechanism for engaging the marginal portion of the insole and pressing it against the bottom of the last before the margin of the upper is laid inwardly over it, means for imparting to said holdown in addition to positioning movement received from said lasting mechanism a further movement relatively to said mechanism to a position opposite the bottom face of the last, and fluid-operated means carried by said lasting mechanism for thereafter moving the holdown heightwise of the last into engagement with the insole.

7. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said mechanism for engaging the marginal portion of the insole and pressing it against the

bottom of the last before the margin of the upper is laid inwardly over it, means also carried by said lasting mechanism for moving the holdown relatively to said mechanism to a position opposite the bottom face of the last in the course of the positioning movement of said mechanism, and a cylinder-and-piston device carried by said lasting mechanism for thereafter moving the holdown heightwise of the last into engagement with the insole by fluid pressure.

8. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said lasting mechanism for engaging the marginal portion of the insole and pressing it against the bottom of the last before the margin of the upper is laid inwardly over it, and means for moving said holdown heightwise of the last into engagement with the marginal portion of the insole after the positioning movement of said lasting mechanism.

9. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said lasting mechanism for engaging the marginal portion of the insole and pressing it against the bottom of the last before the margin of the upper is laid inwardly over it, and fluid-operated means also carried by said lasting mechanism for moving said holdown into engagement with the insole.

10. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown for engaging the marginal portion of the insole and pressing it against the bottom of the last before the margin of the upper is laid inwardly over it, a lever carried by said lasting mechanism and on which said holdown is mounted, and a cylinder-and-piston device also carried by said lasting mechanism for swinging said lever heightwise of the last by fluid pressure to move the holdown into engagement with the insole.

11. In a machine for shaping uppers over lasts, the combination with lasting mechanism having means for laying the margin of an upper inwardly over an insole on a last, and means for imparting to said lasting mechanism positioning movement toward each last and shoe prior to its operation on the upper, of a holdown carried by said lasting mechanism for engaging the marginal portion of the insole and pressing it against the bottom of the last before the margin of the upper is laid inwardly over it, a device also carried by said lasting mechanism and movable by the pressure of operating fluid thereon for moving said holdown into engagement with the insole, and automatic means for admitting operating fluid to said device after the positioning movement of said mechanism and for releasing the fluid from said device at a predetermined time in the operation of said overlaying means on the margin of the upper.

12. In a machine for shaping uppers over lasts, the combination with means for laying the margin of an upper inwardly over an insole on a last, of a holdown for engaging the marginal portion of the insole and pressing it against the bottom of the last before the margin of the upper is laid inwardly over it, a lever supporting said holdown and mounted for swinging movement heightwise of the last to carry the holdown into engagement with the insole, and a cylinder-and-piston device for thus swinging said lever by fluid pressure, said lever being bodily movable relatively to said cylinder-and-piston device to carry the holdown to a position substantially opposite the bottom face of the margin of the insole.

13. In a machine for shaping uppers over lasts, the combination with means for laying the margin of an upper inwardly over an insole on a last, of a holdown for engaging the marginal portion of the insole and pressing it against the bottom of the last before the margin of the upper is laid inwardly over it, a device movable by pressure of operating fluid thereon for moving said holdown into engagement with the marginal portion of the insole and for holding it in such engagement, a spring against the resistance of which said device is thus movable, and automatic means for releasing the operating fluid from said device at a predetermined time in the operation of the overlaying means on the margin of the upper to permit the holdown to be withdrawn from the insole by said spring.

14. In a machine for shaping uppers over lasts, the combination with opposite side-lasting mechanisms each having means for laying the margin of an upper inwardly over an insole on a last, and means for moving said lasting mechanisms inwardly toward the sides of each last and shoe prior to their operation on the upper, of holdowns carried by said mechanisms for pressing the opposite side marginal portions of the insole against the bottom of the last before the upper is laid inwardly over the insole, means for imparting to said holdowns inward movements relatively to said lasting mechanisms to positions opposite the bottom face of the last, and additional means for moving the holdowns heightwise of the last into engagement with the insole.

15. In a machine for shaping uppers over lasts, the combination with opposite side-lasting mechanisms each having means for laying the margin of an upper inwardly over an insole on a last, and means for moving said lasting mechanisms inwardly toward the sides of each last and shoe prior to their operation on the upper, of holdowns carried by said mechanisms for pressing the opposite side marginal portions of the insole against the bottom of the last before the upper is laid inwardly over the insole, automatic means for imparting to said holdowns inward movements relatively to said lasting mechanisms to positions opposite the bottom face of the last in the course of the inward movements of said mechanisms, and additional means carried by said mechanisms for thereafter moving the holdowns heightwise of the last into engagement with the insole.

16. In a machine for shaping uppers over lasts, the combination with opposite side-lasting mechanisms each having means for laying the margin of an upper inwardly over an insole on a last, and means for moving said lasting mechanisms inwardly toward the sides of each last and shoe prior to their operation on the upper, of holdowns carried by said mechanisms for pressing

the opposite side marginal portions of the insole against the bottom of the last before the upper is laid inwardly over the insole, means for imparting to said holddowns inward movements relatively to said lasting mechanisms to positions opposite the bottom face of the last, and fluid-operated devices carried by said mechanisms for thereafter moving the holddowns heightwise of the last into engagement with the insole.

17. In a machine for shaping uppers over lasts, the combination with opposite side-lasting mechanisms each having means for laying the margin of an upper inwardly over an insole on a last, and means for moving said lasting mechanisms inwardly toward the sides of each last and shoe prior to their operation on the upper, of holddowns for pressing the opposite side marginal portions of the insole against the bottom of the last before the upper is laid inwardly over the insole, levers supported on said lasting mechanisms for swinging movements heightwise of the last and on which said holddowns are mounted, means for moving said levers bodily widthwise of the last relatively to said mechanisms to carry the holddowns to positions opposite the bottom face of the last, and means for thereafter swinging said levers to move the holddowns into engagement with the insole.

18. In a machine for shaping uppers over lasts, the combination with opposite side-lasting mechanisms each having means for laying the margin of an upper inwardly over an insole on a last, and means for moving said lasting mechanisms inwardly toward the sides of each last and shoe prior to their operation on the upper, of holddowns for pressing the opposite side marginal portions of the insole against the bottom of the last before the upper is laid inwardly over the insole, levers supported on said lasting mechanisms for swinging movements heightwise of the last and on which said holddowns are mounted, means for moving said levers bodily widthwise of the last relatively to said mechanisms to carry the holddowns to positions opposite the bottom face of the last, and cylinder-and-piston devices carried by said mechanisms for thereafter operating said levers by fluid pressure to move the holddowns into engagement with the insole.

19. In a machine for shaping uppers over lasts, opposite side-lasting mechanisms each provided with a plurality of fingers for laying the margin of an upper inwardly over an insole on a last and each including also a member movable heightwise of the last to impart to said fingers swinging movements to press the margin of the upper on the insole, means for moving said lasting mechanisms inwardly toward the sides of each last and shoe prior to their operation on the upper, holddowns carried by said mechanisms for pressing the opposite side marginal portions of the insole against the bottom of the last before the upper is laid inwardly over the insole, devices arranged to be operated by movements of the finger-operating members heightwise of the last in the course of the inward movements of said lasting mechanisms toward the sides of the last to impart to said holddowns inward movements relatively to said mechanisms, and additional means for moving said holddowns heightwise of the last into engagement with the insole.

20. In a machine for shaping uppers over lasts, the combination with opposite side-lasting mechanisms each having means for laying the mar-

gin of an upper inwardly over an insole on a last, and means for moving said lasting mechanisms inwardly toward the sides of each last and shoe prior to their operation on the upper, of holddowns carried by said mechanisms for pressing the opposite side marginal portions of the insole against the bottom of the last before the upper is laid inwardly over the insole, and means carried by said lasting mechanisms for moving said holddowns into engagement with the insole after said mechanisms have thus been moved inwardly toward the sides of the last.

21. In a machine for shaping uppers over lasts, the combination with opposite side-lasting mechanisms each having means for laying the margin of an upper inwardly over an insole on a last, and means for moving said lasting mechanisms inwardly toward the sides of each last and shoe prior to their operation on the upper, of holddowns carried by said mechanisms for pressing the opposite side marginal portions of the insole against the bottom of the last before the upper is laid inwardly over the insole, fluid-operated devices carried by said lasting mechanisms for moving said holddowns into engagement with the insole, and means for admitting operating fluid to said devices after said lasting mechanisms have been moved inwardly toward the sides of the last.

22. In a power-operated machine for shaping uppers over lasts, the combination with opposite side-lasting mechanisms each having means for laying the margin of an upper inwardly over an insole on a last, and means for moving said lasting mechanisms inwardly toward the sides of each last and shoe prior to the starting of the power operation of the machine, of holddowns carried by said mechanisms for pressing the opposite side marginal portions of the insole against the bottom of the last before the upper is laid inwardly over the insole, fluid-operated devices carried by said mechanisms for moving said holddowns into engagement with the insole, and means for admitting operating fluid to said devices after the starting of the power operation of the machine.

23. In a machine for shaping uppers over lasts, the combination with means for laying the margin of an upper inwardly over an insole on a last along the shank portion of the insole, of a holddown for engaging the marginal portion of the insole and pressing it against the bottom of the last in that location before the margin of the upper is laid inwardly over it, said holddown comprising a resilient metal member arranged to extend along the margin of the insole and flexibly yieldable heightwise of the last to conform to the contour of the different portions of the last and insole along which it extends.

24. In a machine for shaping uppers over lasts, the combination with means for laying the margin of an upper inwardly over an insole on a last, of a holddown for engaging the marginal portion of the insole and pressing it against the bottom of the last before the margin of the upper is laid inwardly over it, said holddown comprising a coil spring arranged to extend lengthwise along the margin of the insole in pressure-applying relation thereto and flexibly conformable to the contour of the last and insole.

25. In a machine for shaping uppers over lasts, the combination with means for laying the margin of an upper inwardly over an insole on a last, of a holddown for engaging the marginal

portion of the insole and pressing it against the bottom of the last before the margin of the upper is laid inwardly over it, said holddown comprising a coil spring arranged to extend lengthwise along the margin of the insole in pressure-applying relation thereto, and a resilient member extending into the opening in said spring to support the spring, said member and spring being both flexibly yieldable heightwise of the last to conform to the contour of the last and insole.

26. In a machine for shaping uppers over lasts, the combination with means for laying the margin of an upper inwardly over an insole on a last, of a holddown for engaging the marginal portion of the insole and pressing it against the bottom of the last before the margin of the upper is laid inwardly over it, said holddown comprising a coil spring arranged to extend lengthwise along the margin of the insole in pressure-applying relation thereto, and a resilient member extending into the opening in said spring to support the spring, said member being generally smaller than the diameter of the opening in the spring but having thereon larger means in said opening supporting the ends of the spring while leaving the intermediate portion of the spring normally spaced from the member.

27. In a machine for shaping uppers over lasts, the combination with means for laying the margin of an upper inwardly over an insole on a last along the shank portion of the insole, of a holddown for engaging the marginal portion of the insole and pressing it against the bottom of the last before the margin of the upper is laid inwardly over it, said holddown comprising resilient means arranged to extend along the margin of the insole in pressure-applying relation thereto and flexibly yieldable heightwise of the last to conform to the contour of the last and insole, and means for pressing said holddown upon the insole by engaging it in a location substantially midway of its extent along the margin of the insole.

28. In a machine for shaping uppers over lasts, the combination with means for laying the margin of an upper inwardly over an insole on a last along the shank portion of the insole, of a holddown for engaging the marginal portion

of the insole and pressing it against the bottom of the last before the margin of the upper is laid inwardly over it, said holddown comprising a pair of coil springs arranged to extend lengthwise along the margin of the insole substantially in alinement with each other and in pressure-applying relation to the insole, and means for supporting the holddown in a location between the two springs.

29. In a machine for shaping uppers over lasts, the combination with means for laying the margin of an upper inwardly over an insole on a last along the shank portion of the insole, of a holddown for engaging the marginal portion of the insole and pressing it against the bottom of the last before the margin of the upper is laid inwardly over it, said holddown comprising a pair of coil springs arranged to extend lengthwise along the margin of the insole substantially in alinement with each other and in pressure-applying relation to the insole, resilient means extending into the openings in said springs for supporting the springs and flexibly yieldable heightwise of the last with the springs to conform to the contour of the last and insole, and a support for said resilient means between the springs.

30. In a machine for shaping uppers over lasts, the combination with means for laying the margin of an upper inwardly over an insole on a last along the shank portion of the insole, of a holddown for engaging the marginal portion of the insole and pressing it against the bottom of the last before the margin of the upper is laid inwardly over it, said holddown comprising a pair of coil springs arranged to extend lengthwise along the margin of the insole substantially in alinement with each other and in pressure-applying relation to the insole, a flexible resilient wire extending into the openings in said springs and of smaller diameter than said openings, said wire having on its ends members of larger diameter located in the openings in the springs to support the springs, and a support for said wire located between the two springs, said support being provided with members of greater diameter than the wire extending into the adjacent ends of the openings in the springs.
